UNITED STATES PATENT OFFICE.

WILLIAM P. WOOD, OF PAWTUCKET, RHODE ISLAND, ASSIGNOR TO JENCKES SPINNING COMPANY, OF PAWTUCKET, RHODE ISLAND, A CORPORATION OF RHODE ISLAND.

BOBBIN-HOLDING MEANS.

1,385,962.

Specification of Letters Patent. Patented July 26, 1921.

Application filed June 29, 1918. Serial No. 242,673.

To all whom it may concern:

Be it known that I, WILLIAM P. WOOD, a citizen of the United States, residing at 34 Brook St., Pawtucket, in the county of Providence and State of Rhode Island, have invented certain new and useful Improvements in Bobbin-Holding Means; and I do hereby declare the following to be a full, clear, and exact description of the invention, 10 such as will enable others skilled in the art to which it appertains to make and use the same.

This invention relates to improvements in bobbin holding means for loom shuttles.

15 Bobbins used in loom shuttles, and more particularly those used in the shuttles of weft replenishing looms, are made of wood and are usually formed with a projection at the butt having ribs or shoulders which 20 are engaged by a tongue on a bobbin catch carried by the shuttle body. With this construction, the wooden ribs are frequently split off by the constant hammering due to the travel of the shuttle back and forth and 25 the sudden starting and stopping of the shuttle, thus delaying the weaving and rendering the bobbin unfit for further use. Considerable loss is occasioned in this way and various kinds of bobbin holders have 30 been devised, but they have not been successful in preventing injury to the bobbins.

The object of this invention is to prevent such wastage of bobbins and loss of time in the weaving by providing improved bobbin holding means for more securely holding the bobbin in the shuttle during the weaving.

To this end the bobbin is held in the shuttle by means of interlocking metallic holding devices, one or more members of which 40 are on the shuttle and one or more coöperating members of which are on the bobbin. The holding devices preferably comprise spurs or fingers arranged to fit within 45 metallic or reinforced sockets, and the spurs are preferably formed on a spring catch plate secured to the shuttle, while the reinforced sockets are preferably formed by embedded metallic bushings in the butt of the 50 bobbin, since this enables the strain on the bobbin member to be more evenly distributed and more effectively withstood.

Referring to the drawings, Figure 1 is a view partly in side elevation and partly in

longitudinal section of a portion of a shuttle, with a bobbin occupying its normal or operative position therein, and showing a preferred form of the invention; Fig. 2 is a similar view showing the bobbin spindle elevated to release the bobbin; Fig. 3 is a bottom plan view of the parts shown in Figs. 1 and 2; Fig. 4 is a perspective view of the butt end of the bobbin; and Fig. 5 is a perspective view of the bobbin catch.

In the illustrated embodiment of the invention, A is the body of the shuttle and B is the bobbin spindle, mounted upon a transverse pivot pin C, and adapted for swinging movement into and out of the recess D within the shuttle. The butt of the bobbin 70 spindle through which the pivot pin passes has two angularly disposed positioning faces E and F on its under side, adapted to coöperate with a spring member to hold the bobbin spindle in its two extreme positions; 75 one being the normal or operative position, and the other being the bobbin receiving and releasing position. The parts so far described are of usual construction.

The bobbin holding means comprises two 80 fingers or spurs 7 projecting upwardly from a spring catch plate 5 which is secured to the shuttle by the screw 6, and which may also form the spring member coöoperating with the spindle positioning faces E and F. 85 The spurs are arranged to engage reinforced sockets 11 formed by inserting metallic bushings 10 in holes bored in a longitudinal tongue 8 which extends diametrically across the butt end of the bobbin G, and is formed 90 with two parallel flat surfaces 9. The tongue is of sufficient thickness to allow the central longitudinal opening H in the bobbin to continue therethrough. The socket holes are bored transversely through 95 the tongue at right angles to the surface 9, one at each side of the central opening H which receives the spindle B. The metallic bushings are inserted in the holes and the ends are rolled over on to the opposite flat 100 surfaces 9 of the tongue so as to hold the bushings securely in place, and also strengthen the tongue about the bushings. Reinforced sockets are thus formed which 105 are open at both ends, and which may readily be engaged with the spurs of the catch.

The bobbin is first placed on the spindle while the latter is in its receiving position,

as shown in Fig. 2, and as it is swung downwardly toward its operative position, the spurs 7 on the bobbin catch enter the sockets 11 in the tongue. Inasmuch as the sockets 5 extend through the tongue, the spurs on the bobbin catch may enter them from whichever end is presented to the prongs as the bobbin is swung into operative position. The rounded ends of the spurs, together with the 10 slightly flared mouths of the sockets, where the bushings are rolled over, aid in guiding the spurs into the sockets. Preferably the bushings are made of brass so that they will not rust and thereby cause injury to the 15 yarn carried by the bobbin.

When the spindle and bobbin are finally positioned, as shown in Fig. 1, the spurs 7 project practically their entire length into the sockets and securely hold the bobbin 20 against longitudinal displacement on the spindle, and also position it with the feeler hole I in proper relation to the replenishing mechanism. The strain resulting from the sudden stopping of the shuttle during 25 the weaving is resisted by the bushings which are firmly seated within the wooden tongue of the bobbin, so that they will effectively resist the strains and shocks to which they are subjected without danger of 30 breaking the tongue or of becoming detached therefrom.

While the invention has been herein described and illustrated by the drawings in accordance with what is now considered to 35 be the preferred embodiment thereof, it will be understood that changes in the form and arrangement may be made without departing from the spirit and scope of the claims.

Having described the invention, what is 40 claimed is:—

1. In a shuttle, the combination with the bobbin and the bobbin spindle, of a longitudinal tongue at the butt end of the bobbin having a socket extending transversely therethrough, and a spur on the shuttle body adapted to engage said socket when the bobbin is inserted to lock the bobbin against longitudinal displacement or turning on the bobbin spindle.

2. In a shuttle, the combination with the bobbin and the bobbin spindle, of a longitudinal tongue projecting from the butt end of the bobbin having sockets extending transversely therethrough, and bobbin holding means on the shuttle body adapted to coöperate with said sockets to hold said bobbin against longitudinal displacement in the shuttle and positively prevent the bobbin from turning on the bobbin spindle.

3. In a shuttle, the combination with the bobbin and the bobbin spindle, of a longitudinal tongue at the butt end of the bobbin having a transverse recess therein, a bushing in said recess, and a bobbin catch on the 65 shuttle body having a spur adapted to enter

said bushing when the bobbin is inserted in the shuttle to lock the bobbin against longitudinal displacement or turning on the bobbin spindle.

4. In a shuttle, the combination with the 70 bobbin and the bobbin spindle, of a longitudinal tongue at the butt end of the bobbin having reinforced sockets extending transversely therethrough, a bobbin catch on the shuttle body, and spurs projecting from said bobbin catch adapted to enter said sockets to lock the bobbin against longitudinal displacement or turning on the bobbin spindle.

5. In a shuttle, the combination with the 75 bobbin and the bobbin spindle, of a longitudinal tongue at the butt end of the bobbin having recesses extending transversely therethrough, bushings in said recesses, a plate secured at one end of the shuttle body, and spurs projecting from the opposite end of 80 said plate and adapted to enter said bushings when the bobbin is inserted in the shuttle to lock the bobbin against the longitudinal displacement or turning on the bobbin spindle.

6. In a shuttle, the combination with the 85 bobbin and a pivoted bobbin spindle having positioning faces at its pivoted end, of a tongue projecting longitudinally from the butt of the bobbin and having holes extending transversely therethrough, bushings in 90 said holes, a spring plate secured at one end to the shuttle body and adapted to coöperate with said positioning faces to hold said bobbin spindle in operative and inoperative positions, and spurs on said plate to engage 95 said bushings when said bobbin spindle is swung into operative position to lock the bobbin against longitudinal displacement or turning on the bobbin spindle.

7. The combination in a shuttle having 100 a pivoted bobbin spindle with positioning faces formed at its pivoted end, of a bobbin catch comprising a spring plate secured at one end to the shuttle body, and adapted to coöperate with said positioning faces to hold 105 said spindle in two positions, spurs on said plate, and a bobbin adapted to be inserted on said spindle when said spindle is in one position and provided with sockets in the butt thereof adapted to be engaged by 110 said spurs when the spindle is in the other position to lock said bobbin against longitudinal displacement or turning on said spindle.

8. A wooden shuttle bobbin having a 115 tongue across its butt end provided with reinforced sockets extending transversely therethrough and adapted to be engaged by 120 bobbin holding prongs on a shuttle.

9. A wooden shuttle bobbin having a 125 tongue across its butt end provided with two transverse holes, and bushings in the holes having their ends rolled over the faces of the tongue.

WILLIAM P. WOOD.
